UNITED STATES PATENT OFFICE.

JAMES W. PATTERSON, OF BRONXVILLE, NEW YORK, ASSIGNOR TO AUTOSALES GUM AND CHOCOLATE COMPANY, OF NEW YORK, N. Y., A CORPORATION OF NEW YORK.

COIN-CONTROLLED VENDING-MACHINE.

1,244,888.

Specification of Letters Patent.

Patented Oct. 30, 1917.

Continuation in part of application Serial No. 235,994, filed December 8, 1904, and division of application Serial No. 335,864, filed September 24, 1906. This application filed March 4, 1910. Serial No. 547,187.

To all whom it may concern:

Be it known that I, JAMES W. PATTERSON, resident of Bronxville, Westchester county, State of New York, have invented an Improvement in Coin-Controlled Vending-Machines, of which the following is a specification.

My invention has reference to coin controlled vending machines and consists of certain improvements which are fully set forth in the following specification and shown in the accompanying drawings which form a part thereof.

This application is a division of my application serial numbered 335,864, filed September 24, 1906, and is specifically directed to the coin controlled feature. Any matters herein shown and described other than in connection with coin controlled mechanism, form subject matter of my aforesaid application, of which this is a division.

This application, as far as the subject-matter of the claims is concerned, is a continuation of applicant's application filed December 8, 1904, Serial No. 235,994, which resulted in Patent No. 837,337, granted December 4, 1906.

The object of my invention as claimed in this divisional application, is to provide a coin-controlled locking mechanism which is normally held in locking position by locking means, the parts being so constructed and arranged relatively to each other that the deposited coin first unlocks the locking means and then causes operation of the locking mechanism itself into releasing position. The locking means for the mechanism which controls a suitable member adapted when released to cause or permit delivery of the vendable articles, positively prevents the accidental movement of this locking mechanism into releasing position.

A further object of my invention is to provide key-controlled means for retaining the coin within the coin-chute after it has operated the locking mechanism. This coin-retaining mechanism is normally locked in retaining position, and the parts are so constructed and arranged that the mere insertion of a suitable key into the slot in the casing automatically unlocks the coin-retaining mechanism and moves it into releasing position.

The coin-controlled lock and coin-retain-

ing mechanism of my invention are exceedingly simple in construction and operation and may be embodied in a casing of small dimensions.

In the broad aspect of my invention, the basic principle of the coin-controlled lock and the coin-retaining mechanism may be mechanically carried out in various ways. A preferred form of construction is shown in the accompanying drawings in which:

Figure 1 is a vertical sectional elevation of a vending machine embodying my invention; Fig. 2 is a front elevation of the same with the front part of the coin controlled lock removed and the lower part in section; Fig. 3 is an elevation of the coin operating means of the lock and of the retainer; and Fig. 4 is a perspective view of the riser removed.

A is the case and is closed on all sides but the top as at C. At a distance below the top of the case is a hinged lid B, which is adapted to close the entrance to the interior of the case, but which may be pushed open when the article and the riser are elevated. The lid B is arranged sufficiently low down that it cannot be reached to open it.

W is the riser and consists of a U-shaped frame conveniently fitting the interior of the case and adapted to slide vertically therein. This riser may be lifted by a handle W' riveted to its bottom and extending through a slot A' in the side of the case. The riser may be of any suitable shape so long as it supports the article and is provided or combined with an outwardly extending part by which to move it. The riser W is provided with upright guide walls, the front wall adjacent to the coin controlled lock being slotted as at W².

D is a locking plate and is movable transversely under the action of the coin. This plate has a backward extension E which acts as a locking bolt for riser W, holding it from being raised. As shown, the locking plate is upon the outside of the wall of the case and the backward extension E is upon the inside, it passing through a slot e in the wall of the case. The locking plate D is provided with a stud F against which the coin is forced for moving the plate to the left (Fig. 2) to release the riser.

A dog M is pivoted to the case and spring pressed by spring N to engage a notch on the locking plate, as shown, to keep it in

locking position. This dog M has a projection *m*, against which the coin is forced for depressing the dog and releasing the locking plate D, just as the coin is forced against 5 the part F of the locking plate.

The coin is guided by a coin slot H H' in the front plate G of the lock. It is a notched disk which may be rotated by a knob or handle K extending to the outside of the plate G 10 as shown in Fig. 1. The coin is placed in the slot H at the top of the machine and passes downward until it is received in one of the notches of the disk. The rotation of this disk carries the coin past the pivoted pawl 15 and then downward against the projection *m* of the dog M. This releases the locking plate D and a further movement of the disk carries the coin against the projection F of the locking plate and shifts the plate to release the riser. The coin now descends the slot H and is sustained by the retainer P. This retainer is locked in retaining position by tumblers Q and is normally forced into locking position by the spring T. To unlock 20 or withdraw the retainer P, a pivoted lever R is employed. A suitably shaped key is adapted to enter the slot S and simultaneously lift the tumblers Q and move the lever R, with the result that the retainer P is 25 drawn back and held there so long as the key remains in place. When the key is withdrawn the retainer P is forced back into retaining position by the spring T.

To lock the riser W, it is lowered, and 30 then by a suitable key, inserted in the slot L' and pressed against the lug L on the locking plate, said plate is forced into locking position, as shown. In this manner the lock is reset or locked by hand and unlocked 40 by the coin.

A projection *d* may be formed on the locking plate and adapted to travel into the coin slot H to prevent a coin being inserted except when said locking plate is in locking 45 position. This is important in this box, because the interior of the box cannot be seen and the lid might be closed, even when the case is empty.

The lid B performs the important function 50 of keeping out the dust which would otherwise enter the case upon the article. It is evident that while the hinged lid B is preferable, it may be dispensed with as the article to be sold may be located so far down 55 the case and so snugly fit it, that it cannot be reached for theft.

It is also evident that the box of the article to be vended might be provided with a metallic end to prevent perforation in an 60 attempt to extract the same.

In the operation of the machine, the releasing of the riser W is one hand operation and the lifting of the riser is a second hand operation, the latter being controlled 65 by the former.

This construction of box is inexpensive, because it dispenses with the usual spring acting lifting frames which are necessary in those types of boxes which discharge from the top wholly under control of the coin 70 controlled lock.

In the broad aspect of my invention, the normally locked coin-actuated device D may control any suitable member which in normal position prevents delivery of the goods. 75 Obviously, the particular form and specific mode of operation of this member are immaterial, the main point being that this member is normally held by the device D to prevent delivery of the goods. It is only when the device D has been unlocked and actuated by the deposited coin that the member controlled by said device is moved into a position to cause or permit delivery or withdrawal of the goods.

While I prefer the construction shown, the details thereof may be modified without departing from the spirit of the invention.

Having now described my invention, what I claim as new and desire to secure by Letters Patent, is:—

1. In a coin-controlled lock, a casing having a descending coin-passage open at the bottom, a slidable bolt extending into said passage to retain the deposited coin therein, after its action on the lock, means for mounting said bolt to operate in a plane substantially parallel with the plane of said coin-passage, means for normally locking said bolt in retaining position, and an actuating member for said bolt arranged to operate in a plane parallel with the plane of said bolt, in combination with a key adapted to be inserted into said casing in a plane substantially parallel with the plane of said bolt and coin-passage to first move said locking means into releasing position and then operate said actuating member, whereby said bolt is withdrawn from the coin-passage to release the coin, said bolt being automatically restored into retaining position and said locking means into locking position upon withdrawal of said key.

2. In a coin-controlled lock, a flat casing having a coin-passage and a key-opening arranged in the plane of said casing, said coin-passage being open at the bottom and said key-opening extending inwardly from one of the side walls of said casing, a spring-pressed bolt extending normally into said coin-passage to retain the deposited coin therein after its action on the lock, means engaging said bolt to lock the same in retaining position, and an actuating member for said bolt having a portion extending into said key-opening, in combination with a key adapted to be inserted into said key-opening to first move said locking means into releasing position and then engage said member for actuating the same to retract said bolt,

whereby the retained coin is released, said bolt being automatically restored to retaining position and locked therein upon withdrawal of said key.

5. 3. In a coin-controlled lock having a substantially vertical coin-passage open at the bottom, a horizontally slidable member for holding the coin in said passage after its action on the lock, vertically movable 10 tumblers adapted to lock said member in retaining position, a pivoted element for moving said member into releasing position when unlocked, said member, said tumblers and said element being mounted and arranged to operate in a plane substantially parallel with the plane of said coin-passage, in combination with a key for first moving 15 said tumblers into unlocking position and then operating said pivoted element to shift 20 said retaining member into releasing position, said key operating in a plane substantially parallel with the plane of said coin-passage.

4. In a coin-controlled lock, a casing provided with a coin-passage, a horizontally 25 slidable bolt adapted to retain the coin in said passage after its action on the lock, said bolt being mounted to operate in the plane of said casing, a key-opening extending inwardly from one of the side walls of said 30 casing and substantially parallel with said bolt, a key adapted to be inserted into said slot without being rotatable therein, means for normally locking said bolt in retaining 35 position and adapted to be moved by the inserted key into unlocking position, and a member adapted to be engaged by the inserted key to actuate the unlocked bolt into releasing position.

40. 5. In a coin-controlled machine, a casing provided with a movable element which in normal position prevents delivery of the goods in said casing, movable mechanism having a part adapted to engage said element and hold the same locked, a movable 45 device for normally locking said mechanism in locking position, a coin-engaging member associated with said mechanism, a second coin-engaging member associated with said 50 device, said members being so spaced and arranged as to receive a coin between them and be separated thereby, the coin first engaging said second member to move said device into releasing position and then engaging 55 said first named member to cause actuation of said mechanism into releasing position, and a hand-operable coin-carrier arranged to convey the deposited coin into operative position and discharge the same 60 through the space between said members.

6. In a coin-controlled machine, a casing provided with a movable element which in normal position prevents delivery of the goods in said casing, movable mechanism 65 having a part adapted to engage said ele-

ment and hold the same locked, a movable device for normally locking said mechanism in locking position, a coin-engaging member associated with said mechanism, a second coin-engaging member associated with said 70 device, said members being so spaced and arranged as to receive a coin between them and be separated thereby, the coin first engaging said second member to move said device into releasing position and then engaging 75 said first named member to cause actuation of said mechanism into releasing position, and a rotatable disk having a curved recess to receive the deposited coin, said disk and said coin-engaging members 80 being so arranged that the coin is forced by the pointed end of said recess through the space between said members.

7. In a coin-controlled lock, a casing provided with a movable element which in normal position prevents delivery of the goods in said casing, said casing having a coin-chute arranged substantially in the plane thereof, locking mechanism for said element having a part extending into said coin-chute 85 to be engaged by the coin, whereby said mechanism is moved into releasing position, a device for normally locking said mechanism against operation and having a portion projecting into said coin-chute to be 90 engaged by the coin for moving said device into releasing position, and a rotatable coin-carrier mounted to operate within said coin-chute and adapted to force the deposited coin first against the projecting portion of 95 said device and then against the projecting portion of said mechanism, said coin-carrier having means for forcing the coin out of engagement with said projections through the space between them. 100

8. In a coin-controlled lock, a casing, a hand-operable coin-carrier for conveying the deposited coin into operative position, a transversely movable locking device having a portion in the path of the coin to be actuated thereby, a movable locking member having a portion adapted to engage said device for normally holding the same locked against movement, and a projection on said member arranged below said engaging portion to be engaged by the coin for moving said member into releasing position. 110

9. In a coin-controlled lock, a casing having a front wall provided with a recess, a flat front plate removably secured to said front wall opposite said recess and having a coin-chute formed in its inner side, said front wall forming the rear wall of said coin-chute, a rotatable coin-carrier mounted in said front plate and arranged to operate 120 in said coin-chute, an operating connection extending from said coin-carrier through said front plate to the outside of the casing, a transversely shiftable locking plate arranged within said recess and having a lat- 125 130

5
eral projection extending into said coin-chute, so that the coin engages said projection and shifts said locking plate, a locking device mounted on said front wall for normally locking said plate against operation, and means connected with said device whereby the coin moves the same into releasing position before said coin actuates said plate.

10. In a coin-controlled lock, a casing, a
10 hand-operable coin-carrier for conveying the deposited coin into operative position, a transversely shiftable locking plate having a lateral projection in the path of the coin to be actuated thereby, a pivoted dog for normally locking said plate against operation, and a lateral lug on said dog extending into the path of the coin which thereby actuates said dog and releases the locking plate just before said plate is shifted
15 by the coin.

11. In a coin-controlled lock, a passageway for the deposited coin, a pair of independently mounted members having portions extending into said passageway, one 25 of said members having means for normally locking said other member against operation, said extending portions being so spaced and arranged as to receive a coin between them and to be separated thereby, and a
30 coin-carrier for conveying the coin into engagement with said extending portions to first move said locking member into releasing position and then operate said other member, said coin-carrier having means to force the coin through the space between
35 said portions.

12. In a coin-controlled machine, a casing having a movable element which in normal position prevents delivery of the goods 40 in said casing, a movable device for normally locking said element and having a coin-engaging portion, means for normally locking said device in locking position and also having a coin-engaging portion, said
45 portions being so spaced and arranged as to receive a coin between them and to be separated thereby, and a hand-operated coin-carrier for conveying the deposited coin first against the coin-engaging portion of said locking means to release said device and then against the engaging portion of said device to move the same into releasing position.

13. In a coin-controlled lock, a casing having 55 a front wall provided with a recess, a flat front plate removably secured to said front wall and having a coin-chute extending therethrough, a rotatable coin-carrier mounted on said front plate and arranged to operate in said coin-chute, an operating connection extending from said coin-carrier through said front plate to the outside of the casing, a transversely shiftable locking plate arranged within said recess and adapted to operate therein, a movable locking de-

vice mounted on said front wall for normally locking said plate against operation, and cooperating means associated with said locking plate and said locking device whereby the coin actuated by the carrier first 70 moves said locking device into releasing position and then automatically shifts said locking plate, said coin-carrier being adapted to automatically discharge the coin out of engagement with said cooperating means. 75

14. In a coin-controlled vending machine, a casing provided with a movable element which in normal position prevents delivery of the goods in said casing, movable mechanism mounted in the front wall of said casing and having means for locking said element in normal position, a device mounted in the front wall of said casing independently of said mechanism and adapted to normally lock said mechanism in locking position, a hand-operated coin-carrier adapted to receive the deposited coin and convey the same into operative position, and means whereby the coin actuated by said carrier first moves said locking device into releasing 80 position and then actuates the locking mechanism into releasing position, said locking device being automatically held out of locking engagement with said mechanism when the latter is in releasing position. 85

15. In a coin-controlled lock, a casing having a removable front plate, a coin-passage provided in said plate, a movable bolt mounted on said plate and extending into said coin-passage to retain the deposited coin 90 therein after its action on the lock, said plate having a key-opening or recess extending inwardly from one side thereof, a device mounted on said plate for normally locking said bolt in retaining position, a key 105 adapted to be inserted into said opening or recess without being rotatable therein, and means whereby the mere longitudinal insertion of said key into said opening or recess first moves said locking device into un- 110 locking position and then moves the unlocked bolt into releasing position.

16. In a coin-controlled lock, a flat casing provided with a pair of substantially parallel recesses arranged in the plane of said 115 casing, a coin-passage arranged within said casing in the plane thereof, a bolt mounted in one of said recesses and adapted normally to extend into said coin-passage to retain the deposited coin therein after its ac- 120 tion on the lock, the other recess being open at one side of said casing to receive a key, means for normally locking said bolt in retaining position, a member for actuating said bolt into releasing position, in combination with a key adapted to be inserted into said open recess to move said locking means into unlocking position and actuate said member to retract the unlocked bolt. 125

17. In a coin-controlled lock, a casing hav- 130

ing a coin-passage open at the bottom, a movable bolt for holding the coin in said passage after its action on the lock, movable tumblers arranged to engage said bolt 5 and normally lock the same in retaining position, a movable member adapted to engage said bolt to actuate the same into releasing position, said casing having a key-opening into which said tumblers and said 10 member project, said bolt and said key-opening being arranged in planes substantially parallel with the plane of the coin-passage, in combination with a key adapted to be inserted into said opening to first engage said 15 tumblers and move them into unlocking position and then to engage said member and actuate the same to retract said bolt, the withdrawal of said key automatically restoring said bolt to retaining position and 20 also restoring said tumblers into locking position.

18. In a coin-controlled lock, a casing having a plate provided with an irregularly shaped recess, said casing being also provided with a coin-passage open at both ends, a movable bolt mounted in said recess and extending into said passage to retain the deposited coin therein after its action on the lock, means in said recess for normally locking said bolt in retaining position, an actuating member for said bolt mounted to operate in said recess, a portion of said recess being open to the outside of said casing and constituting a key-opening, said bolt and 35 said key-opening being arranged in planes substantially parallel with the plane of the coin-passage, and a key adapted to be inserted into said opening to first move said locking means into releasing position and 40 then operate said actuating member, whereby the bolt is withdrawn from the coin-passage to release the coin, the withdrawal of said key automatically restoring said bolt to retaining position and also restoring said 45 locking means into locking position.

19. In a coin-controlled lock, a casing provided with a coin-passage open at both ends, a spring-pressed bolt extending into said coin-passage to retain the coin therein 50 after its action on the lock, means for normally locking said bolt in retaining position, and a key adapted upon mere insertion into said casing to unlock said member and retract the same to release the coin, 55 said bolt and said key operating in opposite directions in substantially parallel paths and in the plane of said casing.

20. In a coin-controlled machine, a hand-operable carrier for the deposited coin to 60 carry the same into operative position, a movable device having means to engage the coin on said carrier, whereby the coin actuates said device, a second device mounted independently of said first device and having means for normally locking said first

device against movement, said second device having means to engage the coin on said carrier, said two coin-engaging means being arranged to engage the edge of the coin at substantially opposite points, so 70 that the coin first engages said locking device to move the same into unlocking position and then engages said first device to actuate the same, and means whereby the coin is automatically discharged from between said two coin-engaging means when 75 said first device has been actuated a predetermined amount.

21. In a coin-controlled machine, a passageway for the deposited coin, a movable 80 device having a portion extending into said passageway, a second device mounted independently of said first device for normally locking said first device against movement, said second device having a portion extending 85 into said passageway, and a hand-operable coin-carrier for conveying the coin through said passageway first into engagement with the extending portion of said second device to actuate the same into unlocking 90 position, and then into engagement with the extending portion of said first device to actuate the same when unlocked, the coin being automatically discharged out of the coin-carrier when said first device has been 95 actuated a predetermined amount.

22. In a coin-controlled machine, a movable device having a coin-engaging part, a second movable device adapted normally to lock said first device against movement and 100 also having a coin-engaging part, said devices being mounted independently of each other, said coin-engaging parts being so spaced and arranged as to receive a coin between them, and means to convey the deposited coin into the space between said parts and into engagement therewith, whereby said coin first actuates said second device to unlock said first device and then 105 actuates the unlocked first device, the coin being automatically discharged from between said parts after said first device has 110 been moved a predetermined amount.

23. In a coin-controlled vending machine, a casing having a goods-compartment and 115 a movable member which normally prevents delivery of the goods, a device for normally holding said member in a position to prevent delivery of the goods, a second device mounted independently of said first device 120 and normally locking said first device in normal position, said devices having coin-engaging portions so arranged that the deposited coin first engages said second device to move the same into unlocking position 125 and then engages the unlocked first device to move the same into position to release said member for causing delivery of the goods.

24. In a coin-controlled vending machine, a casing having a goods-compartment and a 130

movable member which normally prevents delivery of the goods, a device for normally holding said member in a position to prevent delivery of the goods, said device having a projection in the path of the deposited coin, a second device pivotally mounted independently of said first device and having means to engage said first device for normally locking the same in normal position 10 to prevent delivery of the goods, said second device having a projection extending into the path of the deposited coin, said projections being so arranged that the deposited coin first engages said second device 15 to move the same into unlocking position and then engages the unlocked first device to move the same into position to release said member for causing delivery of the goods.

20 25. In a coin-controlled vending machine, a shallow and substantially rectangular casing having a goods-compartment, a movable

member which normally prevents delivery of the goods, a device mounted on the front wall of said casing for normally holding said member in a position to prevent delivery of the goods, a second device also mounted on said front plate independently of said first device and normally locking said first device in normal position, said devices having coin-engaging portions so arranged that the deposited coin first engages said second device to move the same into unlocking position and then engages the unlocked first device to move the same into 35 position to release said member for causing delivery of the goods.

In testimony of which invention, I hereunto set my hand.

JAMES W. PATTERSON.
